P. O. HOAG

BADGE

Filed July 23, 1925

FIG. 1.

Fig. 2.

A technical drawing of a mechanical assembly. At the top, the text 'III-3.' is written above a horizontal line. Below this line, a rectangular component is shown with a central slot. Number '4' is placed above the slot. Number '8' is at the top left, pointing to a vertical slot. Number '15' is at the top right, pointing to a vertical slot. Number '5' is at the bottom left, pointing to a vertical slot. Number '1' is at the top right, pointing to a vertical slot. Number '13' is in the center, pointing to a slot. Number '10' is on the right, pointing to a vertical slot. Number '5' is on the right, pointing to a vertical slot. Number '9' is on the left, pointing to a curved slot. Number '16' is at the bottom left, pointing to a curved slot. Number '11' is at the bottom center, pointing to a curved slot. Number '12' is at the bottom right, pointing to a curved slot.

Philip O. Boag INVENTOR

BY Denton ^{and} Thompson
ATTORNEYS

UNITED STATES PATENT OFFICE.

PHILIP O. HOAG, OF NEWARK, NEW JERSEY.

BADGE.

Application filed July 23, 1925. Serial No. 45,600.

This invention relates to certain new and useful improvements in badges, and more specifically to a structure for attaching a pin to a ribbon badge, or in some cases a button. 5 Heretofore, in the manufacture of ribbon badges, it has been generally customary to either sew or glue the ribbon to the pin or its securing means, and the pin has had a tendency to wobble and be unstable, and for 10 that reason it is difficult to attach it to the clothing.

Further, heretofore the cost of manufacture has been relatively great and the resultant product somewhat unsatisfactory because of the appearance of the attachment 15 and the stitching and the limitation as to embossing.

The main object of this invention is to produce a badge that is economical in construction and cost of manufacture, omitting stitching and gluing, and permitting embossing of the entire front of the ribbon, if desired, and in which the pin is stable and 20 the ribbon effectively secured thereto, and in which the attachment is not visible while 25 the badge is being worn.

Other objects and advantages relate to the details of the structure, all as will more fully appear from the following description, 30 taken in connection with the accompanying drawings, in which:

Figure 1 is a perspective view of the attachment from the front.

Figure 2 is a perspective view of the attachment from the back.

Figure 3 is a section on line 3-3, Figure 1, illustrating a ribbon in place.

Figure 4 is a section on line 4-4, Figure 1, illustrating a ribbon in place.

Figure 5 is a section on line 5-5, Figure 3.

The structure as shown comprises a base plate 1 which is slightly concave longitudinally, and has its opposite edges 2 and 3 curled or bent inwardly and its central portion provided with in this instance an integral lug 4 drawn or struck up from the plate. The cooperating back plate 5 is also slightly concave longitudinally, or has its opposite edges 6 and 7 curled or bent inwardly so that the back plate 5 is of slightly less width than the base plate 1, and its edges 6 and 7 register with the inner faces of the edges 2 and 3 respectively, and are adapted 50 to clamp firmly between them an article, such as the ribbon 8.

The backing plate 5 is formed with a centrally disposed backing slot of a size adapted to receive the lug 4 and with additional slots 9 and 10 upon opposite sides of the central slot for a purpose about to be described. The pin 11 may as shown, be formed of a single piece of wire, and is threaded through the openings or slots 9 and 10 in the back plate 5 with the coil 6 60 adjacent or in the slot 9 and the loop 12 adjacent to the slot 10.

The intermediate portion 13 of the pin is crimped or bent transversely and positioned against the inner surface of the back 70 plate 5 and in the space between the back plate and the base plate with the loop 10 extending rearwardly from the back plate 5.

The structure is assembled in a very simple and expeditious manner, as follows, and utilizes a double ribbon with both ends of the ribbon secured to the attachment. As illustrated, each end of the ribbon 8 has a hole pierced through it in the center of the ribbon. In assembling the structure, the 80 hole in the rear flap 14 of the ribbon is put over the lug 4, the front flap is then drawn across the front face of the base plate 1 and turned downwardly across the rear face of the base plate and the opening in that end of the ribbon is placed over the lug 4. The pin is assembled with the back plate 5 and the back plate 5 is pressed with its edges in contact with the ribbon 8 where the ribbon passes by the inner side of the flanges 90 2 and 3, the lug 4 passing through the center slot and the back plate 5, and the end of the lug 4 is then bent over, as best illustrated in Figures 2 and 4 by any suitable means to firmly secure the parts together. 95

The laterally crimped portion of the pin 11 is firmly held against the rear surface of the back plate 5 and prevents wobbling of the pin. The attachment is invisible when the badge is in use, and the badge presents 100 a continuous unbroken front surface well adapted for embossing or the like.

Altho I have shown and described a specific structure as illustrative of a perhaps preferred embodiment of this invention, I 105 do not desire to restrict myself to the details of the same, as various changes may be made within the scope of the appended claims.

I claim:

1. In a structure of the class described, a concave base plate and a concave backing

- plate, one of said plates being of less width than the other, and one of said plates being provided with a lug and the other plate being provided with a slot through which said lug extends, and a ribbon having one end secured to said lug and a portion extending between two adjacent edges of said plates and downwardly across the front of the base plate.

2. In a structure of the class described, a concave base plate and a concave backing plate, one of said plates being of less width than the other, and one of said plates being provided with a lug and the other plate being provided with a slot through which said lug extends, and a ribbon having one end secured to said lug and a portion extending between two adjacent edges of said plates and downwardly across the front of the base plate, and looped back and having its other end extending between the other two adjacent edges of said plate and secured to said lug.

3. In a structure of the class described, a concave base plate and a concave backing plate, one of said plates being of less width than the other, and one of said plates being provided with a lug and the other plate being provided with a slot through which said lug extends, and a ribbon having one end secured to said lug and a portion extending between two adjacent edges of said plates and downwardly across the front of the base plate, and looped back and having its other end extending between the other two adjacent edges of said plates and secured to said lug.

4. In a structure of the class described, a concave base plate and a concave backing plate, one of said plates being of less width than the other, and one of said plates being provided with a lug and the other plate being provided with a slot through which said lug extends, and a ribbon having one end secured to said lug and a portion extending between two adjacent edges of said plates and downwardly across the front of the base plate.

5. In a structure of the class described, a base plate and a backing plate, one of said plates being provided with a lug and the other plate being provided with a slot through which said lug extends, and a ribbon having one end secured to said lug, and a portion extending between two adjacent edges of said plates, and across the front of the base plate.

6. In a structure of the class described, a base plate and a backing plate, one of said plates being provided with a lug and the other plate being provided with a slot through which said lug extends, a ribbon having one end secured to said lug, a portion extending between two adjacent edges of said plates and across the front of the base plate, and looped back around the base plate and having its other end extending between the other adjacent edges of said plates and secured to said plug.

7. In a structure of the class described, a base plate and a backing plate, one of said plates being provided with a lug and the other plate being provided with a slot through which said lug extends, and said backing plate having an additional slot, a pin threaded through said slot and a ribbon having one end secured to said lug and a portion extending between two adjacent edges of said plates and across the front of the base plate.

In witness whereof I have hereunto set my hand this 16th day of July, 1925.

PHILIP O. HOAG.
